UNITED STATES PATENT OFFICE.

HERMON L. VAN VALKENBURG, OF MILWAUKEE, WISCONSIN, ASSIGNOR TO INDUSTRIAL CONTROLLER COMPANY, OF MILWAUKEE, WISCONSIN, A CORPORATION OF WISCONSIN.

SWITCH-MOUNTING.

1,391,809

Specification of Letters Patent. Patented Sept. 27, 1921.

Original application filed July 25, 1918, Serial No. 246,635. Divided and this application filed April 26, 1920. Serial No. 376,473.

To all whom it may concern:

Be it known that I, HERMON L. VAN VALKENBURG, a citizen of the United States, residing at Milwaukee, in the county of Milwaukee and State of Wisconsin, have invented a certain new and useful Improvement in Switch-Mountings, of which the following is a specification.

My invention relates to switch mountings and is especially useful in connection with compensators employed as motor starters. The construction illustrated is the same as shown in my copending application filed July 25, 1918, Serial No. 246,635 of which my present application is a division. Attention is also called to another divisional application for system of motor control, filed on the 14th day of April, 1920, Serial No. 373,771.

The object of my present invention is to provide oil immersed switches so mounted that the contacts may be lifted out of the oil for inspection or repairs without demounting them and without disconnecting them from the supply conductors. Another object is to provide a construction by which the switch contacts may be swung up out of the oil, part of the switch carrying frame remaining pivotally connected to and in place in the inclosing casing. In the particular design shown the switches and switch mountings form part of a hand operated compensator which I will describe so far as may be necessary for a complete understanding of the invention.

I obtain my objects by the mechanism illustrated in the accompanying drawings in which—

Figure 1 is a front elevation of the complete apparatus taken on the line 1—1, Fig. 2.

Fig. 2 is a side elevation on the line 2—2, Fig. 1.

Fig. 3 is a top plan view of the apparatus with the cover removed.

Fig. 4 is a plan section approximately on the line 4—4, Fig. 2.

Fig. 5 is a side elevation similar to Fig. 2, showing the switch parts swung up out of the oil tank for purposes of inspection.

Fig. 6 is similar to Fig. 5 but omits the switch parts for the purpose of better showing the supporting frame in its two positions relatively to the oil tank.

Fig. 7 is a perspective view showing the

lock for holding the pivoted frame down in active position with the switch contact immersed in the oil.

Fig. 8 is a perspective showing the switch operating mechanism. In this figure the parts are separated sidewise, and some of the shafts and pins extended to better reveal the construction and principle of operation. In this sense the figure is diagrammatic, for in the actual structure the mechanism is more compact.

Fig. 9 is a side view of a portion of the outer casing showing the indicating mechanism whereby the operator may determine without opening the casing whether the running switch is open or closed.

Like numerals denote like parts throughout the several views.

In the particular form shown, the casing 1 has a cover (not shown) and in the lower part contains the autotransformer, and the overload relays 4, 5. An oil tank 6 is fastened in the casing above the transformer and contains the oil in which the switches are immersed. A rock shaft 8 is mounted horizontally in the casing, extending from side to side thereof, just above the top of the tank. This rock shaft serves a dual purpose one of which is to operate the switches as will be hereinafter explained. The second function which is more intimately connected with the present invention is to form a pivot bearing for the switch contacts and their operating and supporting elements. According to this particular design of switch mounting there are four plates 16 loosely mounted upon it.

These are rigidly fastened together by transverse bars 17, 18 which are squared so as to be non-rotatable relatively to the plates. These plates and bars constitute a frame pivotally supported on the rock shaft 8, thereby permitting the frame to be swung up so that the switch contacts may be inspected.

When in normal position the front end of the frame is supported by means of lugs 16^a formed on the outer plate 16 and resting upon lugs 1^a extending inward from the side walls 1 of the main casing as shown in perspective in Fig. 7. Locks 1^b

are pivoted to the inside of the side walls 1 as shown in perspective in Fig. 7, and when these are down they prevent the frame from being swung up. When the locks are ro-

tated from the position shown in Fig. 7 the frame may be lifted. It is desirable to provide a handle 19 at the front of the frame whereby it and the switches may be raised 5 up out of the oil for inspection or renewal.

The front bar 17 carries the stationary contacts 20 and 21 of the starting and running switches respectively. The rear bar 18 carries the stationary contacts 38 and 39 10 of the auxiliary switches. A shaft 25 is rotatably supported in the left plate 16 and has rigidly fastened to it the starting switch arms 26 provided at their ends with contacts 27 which engage the contacts 20. Similarly, 15 a shaft 30 is rotatably supported in the right pair of plates 16 and has rigidly fastened to it the running switch arms 31, provided at their ends with contacts 32 which engage the contacts 21. Shaft 30 also has rigidly fastened to it the auxiliary switch arms 34, 35 20 provided at their ends with contacts 36, 37 adapted to engage the stationary contacts 38, 39 fastened to bar 18. The parts are so arranged that when the arms of the running 25 switch are in closed position the arms of the auxiliary switch are in open position and vice versa. As all the switch contacts are carried by the bars or shafts 18, 25 and 30 and these in turn are carried by the frame 30 plates 16, 17, and the latter are pivoted upon the rotatable but otherwise stationary rock shaft 8, it is evident that the switch contacts can be swung up as a unit out of the oil. It 35 is not necessary to disconnect the switch contacts for the purpose, for they are connected by flexible conductors 28 to stationary binding posts 29 mounted inside the back wall of the casing in Figs. 1, 2, 3 and 5. In Fig. 2 the flexible conductors or connectors 40 are shown approximately straight as the switch contacts are immersed in the oil. In Fig. 5 they are shown flexed, with the switch contacts swung up out of the oil. At the binding posts the connectors 28 are electrically connected to any suitable supply 45 conductors 33. Thus it will be seen that the contacts are all carried in a frame which is located above the oil tank or pan and pivoted at a fixed point in such manner that the 50 contacts may all be swung up out of the oil or lowered into it without disturbing the electric connections to the supply conductors.

To illustrate how in this particular piece 55 of apparatus the switches may all be operated through the agency of the shaft 8 which forms the pivotal support for the frame, I will now describe the switch operating mechanism. It is the same as shown and described in my said two co-pending applications, and has an operating handle 10 by 60 which the shaft may be rocked back and forth. A spring 11, best shown in Figs. 1, 3 and 9, constantly urges the handle toward 65 initial position shown in said figures. One

end of the spring overlies the handle while the other end engages a lug 12 fastened on the outside of the casing. This lug forms a stop for limiting the backward movement of the handle, while another lug 13 forms a 70 stop for limiting the forward movement of the handle. The switch contacts together with their supporting arms and shafts, have already been described. One of these shafts, viz., 25, is operated by a plate 40 which is 75 fastened to it.

A spring 41 is fastened at one end to said plate and at the other end to a stationary rod 42. This spring tends to keep the starting switch open. The closure of the starting 80 switch is effected by means of a link 44 adapted to engage the pin 45 projecting from the side of plate 40. Said link is actuated by an arm 47 rigidly fastened to rock shaft 8. The link and the arm are articulately connected by a pin 46 which also performs the function of a trip as hereinafter explained. Link 44 is longitudinally slotted to permit the operating handle to be rotated 85 part way back to initial position while the starting switch remains closed. An arm 48 on the plate 40 serves to limit the movement of shaft 25 and arms 26 and under the influence of spring 41. When the starting 90 switch has reached closed position it is held 95 there by a detent 50 which is pivoted at one end upon the projection 51 on plate 16. A spring 52 urges the free end of the detent upward. Said detent has a slot 53, at one end of which a shoulder 54 is formed. 100 When the pin 45 moves forward and reaches the shoulder 54 the spring 52 causes the shoulder to engage the pin and hold the starting switch closed. The detent has a tail 55 in position to be engaged by pin 46 about 105 the time the operating handle 10 returns to initial position, consequently as the handle reaches initial position on backward movement the pin 46 engages tail 55 and causes 110 detent 50 to release pin 45, thus permitting spring 41 to rotate shaft 25 and swing the starting switch arms 26 to open position.

The shaft 30, which operates the running switch arms 31 and auxiliary switch arms 34, and 35 is operated by a plate 60 which is constantly urged by a spring 61 in a direction 115 to open the switch. The lower end of the spring is attached to rod 42. An arm 64 is formed on plate 60 in position to strike the stationary bar 18 and limit the amount of 120 rotation of shaft 30 under the influence of spring 61. The closure of the running switch is effected by means of a connector link 68, having a shoulder 69 adapted to engage a pin 70 projecting from the side of the arm 71 which forms a part of the plate 60. Said connector link is articulately connected to an arm 74 rigidly fastened to rock shaft 8. The parts are so arranged that when the operating handle 10 is rotated sufficiently for- 125 130

ward the shoulder 69 will engage the pin 70 and close the running switch provided the holdout mechanism permits the connector link to act. This holdout mechanism consists of a pin 76 which underlies a cam 77 formed on the under side of the link. Pin 76 is carried by the plate 40 fastened to the starting switch, and the design is such that if the starting switch is closed, the pin 76 will be out of reach of cam 77, and hence the connector link will be able to engage the pin 70 and close the running switch. But if the starting switch is open, the pin 76 will occupy a position where the cam 77 will ride upon it and will cause the connector link in its forward movement to rise sufficiently to cause the shoulder 69 to clear the pin 70 and thus produce no effect upon it. It will thus be seen that the connector 68 cannot close the running switch unless the starting switch is closed.

When the running switch reaches closed position it is held there by latch or detent 80 pivoted upon a pin 81 having a suitable stationary support. Said detent is overbalanced so as to tend to assume acting position. It is provided with a hook, the front edge 85 whereof forms a cam located in position to be engaged by an anti-friction roller 86 mounted at one end of a link 87. Said link is pivotally supported by the arm 71 of the plate 60 and has a spring 88 for urging its free end downward to engage the hook. As the link moves forward in the direction to close the running switch, it becomes engaged by the hook. The means which I have provided for holding this hooked detent in acting position are electromagnetic and consist in the present case of a stationary winding 90 mounted in position to attract the armature 91 fastened to the rear end of the detent. The parts are so constructed that unless the winding is sufficiently energized, the tension of the spring 61 will be sufficient to disengage the links 87 from the detent and permit the spring 61 to open the running switch. The winding 90 and detent 80 therefore form part of an under voltaged release.

It will be unnecessary to explain the electrical principles on which the compensator operates, as these are not directly concerned with the present invention and are explained in detail in my aforesaid co-pending application Serial No. 246,635.

From the foregoing it will be evident that the switch contacts are immersed in oil under all operating conditions but may be readily swung up out of the oil for inspection or repairs. This can be accomplished without disconnecting the parts electrically. It will also be evident that it is possible to raise and lower the contacts out of and into the oil without mechanically disconnecting them from the parts by which they are actuated.

In other words, the power device (which in

the present case is manually operated, and is in the form of a handle 10), is mounted in fixed position on the stationary casing, while the contacts are not only movable relatively to each other, but are movable in unison into and out of the oil and yet these contacts remain at all times in mechanical connection with power device; and no wrenches, screw drivers or other tools need be used when the inspection is proposed. In fact, no manipulation of the power device or the mechanical connections between it and the switch contacts is necessary. Another advantage in my construction is that it saves material and labor because the shaft 8 is made to perform the dual function of a pivotal support and an actuating shaft.

Having thus described my invention, what I claim as new and desire to secure by Letters Patent is:

85

1. An oil switch having an oil pan, a frame pivoted above the pan and adapted to swing about a fixed axis, a pair of contacts rigidly fastened to the frame, a rock shaft mounted in the frame remote from but parallel to the axis of the frame pivot, and means including a rotary element having an axis concentric with the frame pivot for rocking the rock shaft and thereby causing the contacts to engage and disengage each other.

2. An oil switch having an oil pan, a main operating shaft adapted to oscillate in fixed position relatively to the pan, a frame pivoted to said shaft, a pair of contacts mounted on said frame and adapted to be swung with it into and out of the oil, a rock shaft mounted in said frame at a distance from but parallel to the operating shaft, contacts carried by said rock shaft and adapted to engage and disengage the first mentioned contacts, and means connecting the operating shaft and the rock shaft whereby the oscillation of the operating shaft produces a rocking movement of the rock shaft to operate the contacts mounted thereon.

3. In combination, a starting switch, a running switch, an oil tank, a frame pivoted to said tank and carrying said switches, whereby the switch contacts may be normally immersed in the oil and temporarily swung up out of the oil for inspection, and means for opening and closing said switches, said means including an operating handle pivoted coaxially with the frame, and mechanism actuated by said handle for operating said switches individually.

4. A motor starter having a starting switch, a running switch, an oil tank, a rock shaft axially fixed relatively to said tank, a frame pivotally mounted on said shaft and carrying the switches, means actuated by said shaft for opening and closing the switches, and an operating handle for rocking said shaft.

130

5. A motor starter having a starting switch, a running switch, an oil tank, a rock shaft fixed relatively to said tank, an operating handle for operating said rock shaft, a frame pivotally mounted on said shaft, and carrying the switches, the movable elements of said switches being pivoted to said frame, arms coaxial with said switches for operating them, and links actuated by the rock shaft for operating said arms. 25
6. A motor starter having a starting switch, a running switch, an oil tank, a rock shaft axially fixed relatively to said tank, a frame pivotally mounted on said shaft and carrying the switches, means actuated by said shaft for opening and closing the switches individually, an operating handle for rocking said shaft, and a stationary detent for holding the running switch closed. 30
7. A motor starter having a starting switch, a running switch, an oil tank, a rock shaft axially fixed relatively to said tank, a frame pivotally mounted on said shaft and carrying said switches, means actuated by said shaft for operating the switches individually, manual means for rocking said shaft, and an indicator secured to the running switch and visible from a point outside the oil tank for indicating whether the running switch is open or closed. 35
8. A motor starter having a starting switch, a running switch, an oil tank, a manually operated rock shaft axially fixed relatively to said tank, a frame pivotally mounted on said shaft, switch shafts pivotally mounted in said frame and having the movable contacts of the switches secured thereto, whereby the rotation of said switch shafts opens and closes the switches, arms fastened to and extending from said switch shafts, links for actuating said arms, and means operated by the rock shaft for operating said links. 40

In witness whereof, I have hereunto subscribed my name.

HERMON L. VAN VALKENBURG.
